DESIGN FOR A GARMENT HANGER

Nathaniel M. Olney, Jersey City, N. J.

Application March 17, 1941, Serial No. 99,655

Term of patent 7 years

To all whom it may concern:

Be it known that I, Nathaniel M. Olney, a citizen of the United States, resident of Jersey City, in the county of Hudson and State of New Jersey, have invented a new, original, and ornamental Design for a Garment Hanger, of which the following is a specification, reference being had to the accompanying drawing, forming part thereof.

Figure 1 is a side elevational view of a gar-

ment hanger in a closed position, showing my new design; Fig. 2 is a top plan view of the same; Fig. 3 is a front elevational view of the same; Figure 4 is a side elevational view of a garment hanger in an open position.

I claim:

The ornamental design for a garment hanger, substantially as shown and described.

NATHANIEL M. OLNEY.
